PANEL FRONT FOR COIN DISPENSING MACHINES OR SIMILAR ARTICLE

Stuart H. Lane, Coshocton, Ohio

Application November 18, 1954, Serial No. 33,147

Term of patent 14 years

(Cl. D52—3)

Figure 1 is a perspective view of a panel front for coin dispensing machines or similar article showing my new design.

The characteristic features of the design reside in the portions shown in solid lines.

I claim:

The ornamental design for a panel front for coin dispensing machines or similar article, substantially as shown and described.
